To all whom it may concern:

Be it known that I, Helene Pons, a citizen of the United States, residing at New York city, in the county and State of New York, have invented a new, original, and ornamental Design for a Blouse, of which the following is a specification; reference being had to the accompanying drawing, forming a part thereof.

Fig. 3 is a front view of the blouse shown in Fig. 1, with the belt shown as fastened on the wearer.

Fig. 4 is a view similar to Fig. 1, but showing the garment as completely tied on a wearer.

The dominant features of the design reside in the portions shown in full lines.

I claim:

The ornamental design for a blouse, substantially as shown and described.
